UNITED STATES PATENT OFFICE.

GILBERT A. ROTH, OF HASTINGS, NEBRASKA.

LUGGAGE-CARRIER.

1,399,154.

Specification of Letters Patent.

Patented Dec. 6, 1921.

Application filed August 25, 1919. Serial No. 319,526.

To all whom it may concern:

Be it known that I, GILBERT A. ROTH, a citizen of the United States, residing at Hastings, in the county of Adams and State 5 of Nebraska, have invented certain new and useful Improvements in Luggage-Carriers, of which the following is a specification.

This invention relates to improvements in luggage carriers, having as its objective the 10 provision of a simple and efficient attachment which will serve to retain articles both large and small upon the running board of a motor vehicle without injury to the body of the vehicle or likelihood of accidental 15 placement.

The invention comprehends the provision of an arrangement of parts to permit of the carrying of containers of different types, certain of these parts being subject to interlocking connection or attachment one upon another depending upon the necessities arising from the character of the articles to be carried.

It is further a primary object to provide a 25 carrier of foldable construction such that it may be employed when extended to hold large objects, as for example, crates, boxes, trunks, or the like, but with smaller articles to be folded into more compact form and 30 in which form the parts assume a relation to each other inclosing the objects or parcels.

These and such other objects as may hereinafter appear are attained by the novel construction, combination and arrangement of 35 parts to be hereinafter specifically described and claimed. Reference will now be had to the accompanying drawings forming a part of this specification, wherein:

Figure 1 is a side elevation of a motor 40 vehicle having my carrier device applied thereto.

Figs. 2, 3 and 4 are side, end, and plan views of certain of the standards used.

Fig. 5 is an end view of the foldable portion or unit of the carrier, showing in full lines its extended position and in dotted lines its folded position.

Fig. 6 is a plan view of the unit as shown in Fig. 5.

50 Figs. 7 and 8 are detailed views showing the method of interlocking the units together.

Fig. 9 is a fragmentary view of the foldable carrier with the outer side section lowered and a standard 1 arranged in interlocking relation.

Fig. 10 is a section view on the line 10—10 of Fig. 9.

Figs. 11 and 12 are enlarged side and plan views, respectively, showing the construction 60 of the longitudinal bars of the foldable carrier, and

Fig. 13 is a section view on the line 13—13 of Fig. 12.

Throughout the following detail description and on the several figures of the drawings, similar parts are referred to by like reference characters.

Referring to the drawings, and specifically describing the invention, A in Fig. 1 comprises an arrangement of standards, more clearly shown in Figs. 2 to 4, particularly designed to hold such articles as milk containers, but of course, I do not wish to indicate by this that said arrangement may not 75 be used for other articles, as will be found true in the further explanation of my idea. As regards this feature or unit, however, I employ one or more standards 1 each of which is provided at its lower edge with 80 spaced horizontal arms 2 between which the running board of the vehicle is received in attaching, and with a swivel locking or clamping screw 3 to prevent accidental displacement of the standard. Any suitable 85 number of standards are used in spaced relation, as shown in Fig. 1, and by passing straps 4 around the articles resting upon the running board and through openings 5, a series of which at different heights are 90 formed in the standards, said articles are held fast against displacement.

Passing now to the more important feature of my attachment, B in Fig. 1, refers to a carrier unit which is devised particularly to carry such parcels as egg crates, trunks, or even lumber, and the like, and with which the standards of the unit A are adapted to coöperate for certain purposes. The unit B consists of a pair of spaced bottom members 6 formed with the clamping arms 7 and clamping screws 8 to secure the device to the running board. Connecting bars 9 complete the bottom section. To the inner ends of the members 6 is hingedly connected the inner side section formed of the cross pieces 10 and longitudinal bars 11 similar to the bars 9. This section folds from a vertical position downward upon the bottom section when not in use, and is designed to prevent the containers from jarring against the body of the vehicle and 100 105 110

thereby marring its finish. The folding of this section also permits the door of the vehicle to be opened without interference when the carrier is not in use.

- 5 The outer side section is hinged to the bottom section and consists also of the cross pieces 12 and the longitudinal bars 13, each of these bars having connected at its ends a right-angle shaped arm 14, the object of which is to provide end members for the carrier whether this outer section is in folded or unfolded position, as is shown most clearly in Fig. 5. It will be observed, furthermore, that the extremities of the pieces 10 and 12 10 are pointed and apertured so that when the outer side section is in vertical position, removable cross pieces 15 each having apertures at its ends, may be inserted upon said members 10 and 12, thus holding the inner and outer side sections in vertical position 15 and confining the contents of the carrier by complete inclosure. Cotter pins 16 prevent the displacement of the bars 15. It should be noted that the bottom bars 6 from a median point incline upwardly from the horizontal and that the outer side section when extended, as shown in Fig. 5, alines with the incline, the object of this being to cause a tendency of the articles disposed upon the 20 carrier to work inwardly rather than outwardly of the carrier, eliminating the necessity of strapping the objects to the carrier. It will be apparent that the construction of carrier above described greatly enlarges its 25 capacity for holding articles, and extends its usefulness in holding articles which ordinarily are difficult to support by reason of their length or bulk, such as lumber or trunks.
- 30 40 The carrier unit B is capable of use alone, as is true also of the unit arrangement A, but both may be applied together to the running board as shown in Fig. 1. Furthermore, one of these may coöperate with 45 the other by interlocking connection so as to assist in one way or another in carrying out the functions of carriage. For example, as shown in Fig. 7, the arm 7 of a bottom member 6 is provided with a link 17 pivotally connected at 18 and notched at 19 near its outer end. When a standard is juxtaposed with reference to this bottom member, the link is hooked to the clamping screw 3 so that this standard will assist in 50 giving greater security to the carrier B by its additional gripping action and, of course, when so connected the carrier A will also receive support against accidental displacement due to vibrations of articles held thereby. When carrying lumber of any length 55 the outer side section of carrier unit B is lowered to what I call extended position and the lumber placed thereupon, the standards 1 being attached to the running board 60 65 also, after the manner shown in Fig. 1, so

as to prevent the ends from flapping against the side of the vehicle, or providing means to which the ends of the lumber may be tied for end support. The interlocking arrangement with the outer carrier section in 70 its lowered or extended position for the above purpose is shown best in Figs. 9 and 10.

It will be understood that one or more of the standards 1 may be attached to the longitudinal bars of the carrier unit B instead of upon the running board. This will be desirable where the outer side section of the foldable carrier is in extended position and it is desired to prevent articles held thereon 75 from moving outwardly or being jarred off of the carrier, the same being accomplished by attaching one or more of the standards 1 to the outer bar of the outer foldable section.

Not only is the carrier unit B extendable as above described, but it is also capable of being enlarged with respect to its length. Each of the longitudinal bars of the sections is really composed of adjustable members, 90 as will be apparent from Figs. 11 to 13. The section *a* of the bar coöperates with the section *b*, being held in place by means of the keeper *c*. The cross pieces of the various sections may thus be separated to 95 increase the length of the foldable carrier as may be required by the size of the articles which it is desired to carry.

Having thus described my invention, what I claim as new is:

1. A luggage carrier of the class described comprising a bottom section having means for attachment to the running board of a vehicle, a foldable section hingedly connected thereto and adapted to project in 105 alinement with the bottom section when unfolded and to engage a load in either position, and end members projecting laterally from the foldable section and arranged to prevent displacement of articles in a direction endwise of the carrier when in either extended or folded position.

2. A luggage carrier of the class described comprising a bottom section having clamping means for securing it in position upon the running board of a vehicle, the bottom section being formed on an incline from substantially the median line upwardly from the plane of the support whereby an article disposed thereon will tend to move inwardly 115 rather than outwardly, means connected to the inner edge of the bottom section to limit the movement in that direction of the article, and a side section hingedly connected to the outer edge of the bottom section and adapted either to be swung into an upright position or tilted outwardly into an inclined position substantially in alinement with the inclined portion of the bottom section.

3. A luggage carrier of the class described 120

comprising a bottom section having clamping means for securing the carrier to the running board of a vehicle or the like, a foldable side section hingedly connected to the edge of the bottom section, both the bottom section and the side section being formed of slidable adjustable bar members whereby the carrier may be adjusted as regards its length, and end members projecting laterally from the foldable side section for engagement with a load to prevent endwise displacement thereof upon the carrier.

5. A luggage carrier of the class described comprising a bottom section having clamping means for securing it in position on the running board of a vehicle, an inner foldable side section adapted to fold down upon the bottom section, an outer foldable side section hingedly connected to the opposite edge 10 of the bottom section and adapted to be folded outwardly into extended position in alignment with the bottom section, said outer side section being arranged when in extended position so as to incline upwardly 15 from the horizontal plane of the bottom section, end members connected to the ends of the outer side section and movable therewith, and means for connecting the inner and outer side sections so as to hold them 20 in upstanding position at right angles to the bottom section.

6. A luggage carrier of the class described

comprising a bottom section having clamping means for securing the carrier to the running board of a vehicle or the like, and foldable side sections hingedly connected to the opposite edges of the bottom section, each section aforesaid being composed of slidable adjustable bar members whereby the carrier may be adjusted as regards its length, and one of the sections being provided with lateral end members to prevent displacement of a load endwise of the carrier.

7. A luggage carrier of the class described comprising a bottom section adapted to fit upon the running board of a vehicle and provided with clamping means for engaging the said running board, inner and outer opposed side sections hingedly connected to opposite edges of the bottom section, lateral arms projecting from the ends of one of the side sections and arranged to overhang the running board when the side section is swung upwardly and to project upwardly when the side section is swung outwardly, said side section being adapted to support a load when swung outwardly and the lateral arms holding the load against longitudinal movement in either position, and means for holding the two side sections in an upright position.

In testimony whereof I affix my signature.
GILBERT A. ROTH.
